CLAIM

The ornamental design for a bed for children, as shown and described.

DESCRIPTION

FIG. 1 is a rear and top perspective view of a bed for children, showing my new design;

FIG. 2 is a front and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged perspective view of detail "9" identified in FIG. 1.

The dashed lines in the figures illustrate portions of the bed for children that form no part of the claimed design.

1 Claim, 9 Drawing Sheets
